CONSTRUCTION OF FILE CABINET DRAWERS

Filed Feb. 17, 1923

2 Sheets-Sheet 2

Harry Zwick,
By his Attorney, Geo. F. Knapp

UNITED STATES PATENT OFFICE.

HARRY ZWICK, OF BROOKLYN, NEW YORK.

CONSTRUCTION OF FILE-CABINET DRAWERS.

Application filed February 17, 1923. Serial No. 619,558.

To all whom it may concern:

Be it known that I, HARRY ZWICK, a citizen of the United States, and a resident of the borough of Brooklyn, in the county of Kings, city and State of New York, have invented certain new and useful Improvements in the Construction of File-Cabinet Drawers, of which the following is a specification.

10 My improvements relate to the manufacture of boxes out of card-board, so called, covering the various grades thereof as known to the trade, or out of any analogous fibrous board material; and particularly to 15 the making of rectangular boxes out of one-piece body blanks, the upsetting or folding into shape of which creates exterior open or grooved edges, which, when covered with the external wrap, afford a beveled or chamfered 20 appearance, and also endanger the integrity of the portions of the wrap spanning and covering these corner grooves, which obviously afford no support for the overlapping portion of the wrap.

25 The main object is to obviate this difficulty, in so far at least as the ends of the box are concerned, and to afford a flush rectangular finish thereto, of the full width of the box, whereby the bevel-edge effect is eliminated; a true rectangular corner effect is 30 produced; and the wrap is supported against extraneous pressure;—and whereby, also, I simplify and cheapen the cost of production, and reinforce and strengthen the box structure in a unitary sense, all as hereinafter 35 more fully set forth.

To this end the invention consists in the specific construction and arrangement of parts described and claimed, a distinctive 40 feature being the use of auxiliary end plates, of full box width and height, which overlap the end edge grooves incidental to the folding or setting up of the body blank, as herein shown and described.

45 My construction results in a stronger box, better adapted to withstand the requirements, of use, than when the box is formed in the older methods.

In the accompanying drawings I exemplify a practical embodiment of my invention as applied to a box of the index cabinet drawer type, although I do not limit myself to this or any particular type of rectangular box, nor to the identical form of 55 body blank or arrangement of component

parts of the box body, to which my auxiliary circumscribing end boards are applied.

With this understanding:

Fig. 1, represents a plan of an economical form of blank cutting embodying a box body 60 blank of the type designated, together with my auxiliary end boards;

Fig. 2, is an exterior perspective view of an end portion of a box made from the blank sections shown in Fig. 1;

Fig. 3, is an interior perspective view of one end portion of a box so made;

Fig. 4, is a top view of one end of the box so made;

Fig. 5, is a transverse section of the box;

Fig. 6, is an elevation of one end of my improved box;

Fig. 7, is a detail view of the blank of a box of this character as heretofore made;

Fig. 8, is a top view of one extremity of the 75 old form of box.

Fig. 9, is a sectional detail taken upon plane of line 9—9, Fig. 8;

Fig. 10, is a sectional detail taken upon plane of line 10—10, Fig. 11, with the end board included;

Fig. 11, is an end view of my box construction, without the end board.

A preferred form of blank cutting is shown in Fig 1, of the drawings, in which *b*, represents the bottom board or section; *s*, *s*, the side members; and *e*, *e'*, the end folds or flaps, between which my auxiliary circumscribing end boards *a*, *a*, are obtained, this method of blank formation representing the utilization of the material to the best 90 advantage. In this figure the dotted lines represent the lines of fold of the main or body portion of the blank.

The folding or upsetting of the main blank *b*, *s*, *s*, *e*, *e'*, on the lines indicated, which are scored on the under side of the blank to facilitate the bending of the material as prescribed, results in the formation of exterior angle grooves *g*, *g*, which are eventually covered and closed by the wrap *w*. But the corner finish thus attained is bevel-shaped or chamfered, as shown more particularly at *i*, in Figs. 5 and 8 of the drawings. This is especially objectionable at the end corners, not only on account of appearance, but more particularly because the portion of the wrap *w*, covering said angular grooves *g*, *g*, is un-supported, so that slight extraneous pressure along these 110

lines of angular band is apt to rupture the wrap and create a ragged appearance, at the same time exposing the end edges of the side members, *s*, *s*, of the box body for contact with, say, the edges of the drawer space in the cabinet to which the box belongs, or with other extraneous objects. Furthermore, this vulnerability of the end corners of the box or drawer detract from the strength, utility, and durability of the whole structure.

Where the box is made in the old way of a one piece blank, as shown in Figs. 7 and 8 of the drawings, the exterior end folds *e*, *e*, which overlap the inflaps *e*, *e*, create bottom grooves *g*, *g*, and side grooves *g*', *g*', as indicated in Figs. 8 and 9, which are objectionable for reasons hereinbefore stated.

By my provision of independent auxiliary circumscribing end boards *a*, *a*, I am enabled to so form the end folds *e*', *e*', in such manner that they rest upon the floor or bottom member *b*, flush with the end edge thereof, as will be understood by reference particularly to Figs. 10 and 11, of drawings,—the spaces *c*, *c*, representing the sockets for the ends of the longitudinal card rests *c*', *c*', usually provided in index boxes or drawers of the character designated,—and *d*, *d*, being the socket holes for the ends of the usual card rod *d*',—these latter features being only incidental to the index box or tray herein used as an illustration of a practical embodiment of my invention; the essential feature of which is the provision of the independent circumscribing end boards, *a*, *a*, of the full exterior area of the box in cross section, as illustrated in Figs. 2, 3, 4 and 6 of the drawings.

These independent full dimension end boards *a*, *a*, not only isolate and protect the side end grooves, *g*, *g*, but they are especially efficacious in connection with the end structure of box body shown in Fig. 11, since they are pasted, not only to the flaps *e*, *e*', but also to the end edges of the box bottom *b*, thereby insuring strength and integrity of box structure, considered in a unitary sense.

Another practical advantage attained by my independent full dimension end boards

a, *a*, is that they may be passed through a pasting machine preparatory to attachment to the end over-laps and bottom of the box body, thereby dispensing with hand pasting in this respect, and greatly facilitating the process of production as well as reducing the cost thereof.

By my invention I thus insure not only strong joint structure, but also attain sharp rectangular end corners, together with reinforced end construction.

What I claim as my invention and desire to secure by Letters Patent is,

1. A file cabinet drawer formed from a one-piece body blank having a bottom, two sides and two ends, the ends being in sections integral with the sides, the sides being folded up from the sides of the bottom, and the ends folded from the ends of the sides, and reinforcing end pieces cut from the blank and of greater length than the distance between the inner faces of the sides of the drawer and secured to the outer faces of the folded end sections and covering the lines of fold of said end sections.

2. A blank for a file cabinet drawer comprising a bottom, sides and end portions, the latter spaced apart and foldable toward each other to form the ends of the drawer, said blank being cut at the ends between the end portions to form detached reinforcing end pieces of a length greater than the distance between the fold lines of said sides.

3. An open-topped file cabinet drawer of the character described comprising a one piece body formed with bottom, sides and ends, said bottom being flangeless, the end portions being in sections each integral with a side with their adjacent edges disposed between said sides substantially adjacent each other, and substantially rigid end pieces overlapping the adjacent ends on the outside of the end portions and secured solely to the outer faces thereof and of an area equal to the full exterior cross section of the box.

HARRY ZWICK.
